CAP FOR FILLING NOZZLES

John Sinko, Chicago, Ill.

Application September 25, 1935, Serial No. 41,962

4 Claims. (Cl. 220—40)

This invention relates to closures or caps for filling nozzles having reference more particularly to the filling nozzles of automobile gas tanks.

The cap of the present invention quite closely follows the structural features of a filling nozzle cap disclosed and claimed in my pending application Serial 710,789 filed February 12, 1934, but embodies an improvement thereon.

The construction disclosed in my aforesaid application includes a steel spring locking bar that is clamped to the under side of the cap and is formed with downwardly inclined end portions, the tips of which pass through slots in the usual internal flange of the nozzle. The locking bar is secured by a flat rivet that passes through a central longitudinal slot in the locking bar, the purpose of the employment of a flat rivet of substantial width engaged with a longitudinal slot in the locking bar being to prevent any relative turning movement of the bar and cap, so as to insure the locking of the cap to the nozzle by the bar when the cap is turned.

Experience has shown that this comparatively long longitudinal slot in the locking bar to accommodate the flat rivet unnecessarily weakens the bar and also limits the degree of spring in the projecting ends of the bar; and the object of the present invention is to provide an improved construction by which the longitudinal slotting of the locking bar is dispensed with, and the degree of elasticity or spring in the arms of the bar is increased.

A practical embodiment of the invention is illustrated in the accompanying drawing, in which—

Fig. 1 is a sectional view of the upper portion of a filling nozzle and the cap applied thereto, taken on the offset line 1—1 of Fig. 2.

Fig. 2 is a similar view in a plane at right angles 40 to that of Fig. 1.

Fig. 3 is a bottom plan view of the cap as shown in Fig. 2, in horizontal section through the filling nozzle.

Fig. 4 is a group view showing the parts of 45 the cap disassembled.

Fig. 5 is a perspective view of the locking bar.

Fig. 6 is a perspective view of the hollow sheet metal boss through which the end portions of the locking bar extend.

Referring to the drawing, 11 designates the upper portion of the usual filling nozzle of a gasoline line tank. These filling nozzles are customarily formed with an internal downwardly turned flange 12 with which the cap or closure inter-

locks under a partial turning movement of the cap.

The cap, as disclosed in my former application above identified, is a two-part cap consisting of an outer disc 13 having a depending peripheral flange 14, and an inner disc 15 formed with an upturned peripheral flange 16 that is interlocked with the inner flange 14. The inner disc 15 is formed with a shallow countersunk portion 15', over the outer portion of which is fitted a hollow sheet metal boss 17 that is formed with an upwardly offset bottom wall 18. The sides of the boss 17 are vertically slotted, as shown at 19 in Fig. 6, and extending across the boss and through the slots 19 thereof is a spring steel locking bar 20, the projecting end portions of which are adapted, when the cap is applied, to pass down through slots 21 (Figs. 2 and 3) in the nozzle flange 12 for engagement with the lower edge of said flange in the locked position of the cap. As indicated in Fig. 2, the lower edge of the flange on either side of each slot is preferably slightly inclined to provide a cam surface for engagement by the ends of the locking bar as the cap is turned, although this feature is not essential.

The countersunk central portion 15' of the inner disc 15, and the bottom wall 18 of the boss 17 are formed with registering narrow slots 22 and 23 respectively, and the locking bar 20 is formed in each side edge with a central narrow notch 24 so shallow that it does not appreciably weaken the bar. 25 designates a relatively thin and wide flat rivet formed with a pair of spaced legs 26 and squared hips 27 on the outer sides of the legs. 28 designates a round flat washer that seats on the countersunk central portion 15' of the inner disc 15, and is formed with a pair of holes 29 spaced to fit the legs 26 of the rivet 25. In assembling the parts, the legs 26 of the rivet are passed upwardly through the slot 23, the notches 24 of the locking bar, the slot 22, and the holes 29, with the hips 27 of the rivet engaged with the under side of the bottom wall 18 of the hollow boss 17, and the upper ends of the legs of the rivet are then swaged over, as indicated in Fig. 2, whereby the parts are securely united, and the locking bar 20 cannot escape or turn relatively to the cap by reason of the engagement of its notches 24 with the legs of the rivet.

Encircling the hollow boss 17 and bearing against the under side of the disc 15 is a comparatively thick fiber or leather washer 30 that seats on the top of the filling nozzle 11. The

parts are so proportioned that when the cap thus seats on the top of the nozzle, the end portions of the locking bar 20 will have passed through the slots 21 with their upper surfaces substantially flush with the free edge of the nozzle flange. To facilitate engagement of the ends of the locking bar with the nozzle flange, the upper surfaces of said ends are slightly convexed transversely, as shown at 20' in Fig. 5, so that the ends of the locking bar will, under a turning movement of the cap, readily engage with the lower edge of the flange, and where this lower edge is given a low cam formation, as indicated in Fig. 2, as the cap is turned, the locking bar will be slightly sprung downwardly thus insuring a tight, leak-proof fit of the cap on the nozzle, and although, as shown in Fig. 1, the central horizontal portion of the locking bar overlies and rests upon the central wall 18 of the hollow boss 17, this wall will yield downwardly sufficiently to permit a spring action in the locking bar substantially from its center to each end;—a feature impossible in the construction of my former application by reason of the fact that substantially the entire flat central portion of the locking bar is gripped by the flat rivet.

I claim:

1. A cap for a filling nozzle, comprising outer and inner discs united at their peripheries, a central boss depending from said inner disc, a locking bar extending through said boss, said locking bar having notches in its side edges so shallow as not to appreciably weaken said bar, and a rivet having a pair of legs extending through said boss and inner disc and the notches of said locking bar.

2. A cap for a filling nozzle, comprising outer

and inner discs united at their peripheries, said inner disc formed with a central countersunk portion, a washer seated in said countersunk portion, a central boss depending from said inner disc, a locking bar extending through said boss, said locking bar having narrow notches in its side edges so shallow as not to appreciably weaken said bar, and a flat rivet having a pair of legs extending through said boss, the notches of said locking bar, said countersunk portion, and said washer, and swaged over on the latter.

3. A cap for a filling nozzle, comprising outer and inner discs united at their peripheries, said inner disc formed with a central countersunk portion having a slot, a washer seated in said countersunk portion having a pair of holes, a central boss depending from said inner disc having a slot, a locking bar extending through said boss having narrow notches in its side edges so shallow as not to appreciably weaken said bar, and a relatively thin and wide flat rivet having a pair of spaced legs extending through the slot of said boss, the notches of said locking bar, the slot of said countersunk portion and the holes of said washer and riveted over on the latter.

4. A cap for a filling nozzle, comprising outer and inner discs united at their peripheries, a central boss depending from said inner disc, a locking bar extending through said boss, said bar having spaced openings, and a rivet having a pair of legs extending through said boss and inner disc and the spaced openings of said locking bar in inter-fitting engagement with said openings, whereby said bar is locked against turning relatively to said discs.

JOHN SINKO.
